UNITED STATES PATENT OFFICE.

ALFRED L. SOHM, OF CHICAGO, ILLINOIS, ASSIGNOR TO SOHM ELECTRIC COMPANY, OF CHICAGO, ILLINOIS, A CORPORATION OF ILLINOIS.

SECONDARY CLOCK.

1,302,603.

Specification of Letters Patent.

Patented May 6, 1919.

Application filed May 21, 1917. Serial No. 169,873.

To all whom it may concern:

Be it known that I, ALFRED L. SOHM, a citizen of the United States, residing at Chicago, in the county of Cook and State of Illinois, have invented certain new and useful Improvements in Secondary Clocks, of which the following is a full, clear, concise, and exact description, reference being had to the accompanying drawings, forming a part of this specification.

My invention relates to secondary clocks.

It is an object of the present invention to provide a step-by-step mechanism which is simple and positive in operation and which automatically locks against false operation.

It is a further object to provide means for unlocking the step-by-step mechanism manually when it is desired to set the same.

A still further object of the invention is to provide an improved and simplified secondary clock.

In the accompanying drawings, I have shown my invention as embodied in a secondary clock, but it is obvious that the step-by-step mechanism therein shown is capable of wider application than the particular mechanism in which I have illustrated the same.

Figure 1 is an elevational view of the secondary clock embodying the principles of my invention, some of the parts being shown in section to more clearly reveal the structure;

Fig. 2 is a view looking at the mechanism from the left with the dial and hour and minute hands removed;

Fig. 3 is a top view of the mechanism;

Fig. 4 is a front view showing the dial, hour and minute hands and other mechanism; and

Fig. 5 is an isolated view showing the position after the disk has been rotated a certain distance, and locked in position.

Similar reference characters are applied to the same parts throughout the several figures.

As shown particularly in Fig. 1, the dial 6 is mounted by means of screws upon studs 7, 7, these studs being fastened to the top and lower portions of a plate 8. This plate has mounted thereon a second plate 9, having an offset portion 10, so as to provide a space 11. The plate 8 carries electromagnets 12, 12, which are preferably secured by means of screws passing into the cores

13, 13. At the rear of these electromagnets, the cores 13, 13 are passed through a supporting member 14. Supported in the plates 8 and 10, and in the member 14, is a spindle 15, the left-hand portion of which is diminished, and has a flat portion 16, so as to properly engage an enlargement of the minute hand 16'. A nut 17 serves to maintain the minute hand in position upon the spindle. This spindle carries a pinion 18, which meshes with the gear 19, to which is secured a pinion 20, which meshes with a gear 21, mounted upon a tapered sleeve 22, rotatably mounted upon the spindle 15. The hour hand 23 has a hub portion 24, which is in frictional engagement with the sleeve 22. As is shown particularly in Fig. 1, the gear 19 and the pinion 20 are loosely mounted upon a pin 25, extending from the plate 10. The ratio of the pinions and gears is such that the minute hand will make twelve revolutions, while the hour hand makes but one. In order to advance both of these hands at the proper time, I have an arrangement in the form of a disk 26, which is secured upon the spindle 15, and occupies the space 11 between the plates 8 and 10, and, as is shown in Fig. 2, is provided with a plurality of circular openings 27. There are preferably sixty of these openings, and they are disposed concentrically with the spindle 15. The disk, and the parts thereon, are held in a locked position by means of a locking stud 28, the right-hand end of which is rounded so as to be readily forced into any one of the openings 27, when said opening is in alinement therewith. It will be noted that each of the openings 27 is countersunk on both faces of the disk 26. The stud 28 is slidable in a sleeve 29 secured in the plate 10 and has a groove 30, which is engaged by the fingers 31 of the spring 32, whose lower end is bifurcated, at 33, and secured by means of pins 34 to the plate 10.

The supporting member 14 has two lugs, 35, 35 for pivotally mounting the armature 36, the lower end of which has a tongue 37 which normally bears against a tongue 38 on the supporting member 14. The armature has an extension 39 which terminates in a circular pin portion 40, which passes through an opening in the disk rotating arm 41, thus forming a swivel joint. A pin 42 serves to maintain the arm 41 in position. The arm 41 has a lug 43 to which is secured

one end of the spring 44, the other end of which is secured to an extension 45 from the supporting member 14. This spring, it will be noted, serves to normally hold the armature 36 and arm 41 in their normal positions. The forward end of the arm 41 is in the form of a pin 46, whose end is rounded so as readily to engage in any one of the openings 27, which may be in alinement therewith. Normally, this pin portion is held against one end of an opening 47 occurring in the plate 8, by means of the spring 44.

The electromagnets 12, 12 are provided with suitable terminals, only one of which is shown, which are connected to a circuit including a suitable source of power. This circuit, it will be understood, includes a master-clock whose operation determines the energization of the electromagnets and consequently the advancement of the minute and hour hands. When such energization is effected, the armature 36 is attracted, thus causing a forward advancement of the disk rotating arm 41. Thereupon, the rounded portion 46 engages the stud 28, and forces it out of the opening in the disk which it engages at that time. This part of the movement of the arm unlocks the disk in order that it may be advanced in a clockwise direction. The concluding movement of the arm 41 brings the cam portion 48 against the rounded stud 49 carried by the plate 8, and, since the pin portion 46 has forced the stud 28 out of the opening, the disk 26 will be rotated until it is again locked by the stud snapping into the succeeding opening in the disk. The opening 47 may be made of such length as to also determine the amount of rotation of said disk, although this is not absolutely essential. The parts are then in the position shown in Fig. 5, wherein the arm 41 has completed its stroke, and upon deenergization of the electromagnets 12, the spring 44 will draw the arm back into its normal position, as shown in Fig. 3. It will be seen that the advancing action and the subsequent locking of the disk 26 is positive, and, further, that during such advancement there is practically no friction offered by the stud, owing to the conformation of its end, and also to the fact that the openings 27 are countersunk.

In setting the clock after it has been installed, it is desirable that easily accessible means be provided for unlocking the disk in order that the hands may be rotated. To this end, I have provided a disk unlocking member 50 pivoted at 51 to the plate 10. This member 50 has a finger 52 extending through a slot 53 in the dial 6, this slot, of course, being concentric with the pivot point 51. The member 50 has an opening 54 through which the sleeve 29 projects. The opening 54 allows of a range of move-

ment sufficient to throw the locking stud 28 into and out of locking position. A cam portion 55 is provided upon the member 50 and is adapted for engagement underneath the spring 32 when the member 50 is rotated to its active position, so that the finger piece 52 occupies the right-hand end of the slot 53, thereby withdrawing the stud 28 from the opening which it engages at that time. The disk 26 is thus unlocked and the minute and hour hands may be revolved to set the clock, after which the member 50 may be rotated back to its normal position, whereby locking of the disk 26 is again effected. 80

By means of the mechanism embodying my invention, a quick and positive action of the advancement of the minute and hour hands is secured, in addition to locking them in position after each advancement; and the clock 85 is thereby maintained in synchronism with a master-clock, which determines the energization of the electromagnets.

One of the important features of my invention is the fact that the disk 26 may be manually unlocked by means of the readily accessible unlocking device disposed so as to be manually operated without disturbing the adjustment of any of the parts. This has its advantage in the fact that the clock 95 may be completely installed and then set in synchronism with the master-clock with the least amount of work.

While I have herein shown and described certain features of my invention, I do not 100 wish to be limited to the precise arrangement shown, since it is apparent to those skilled in the art, that modifications may be made without departing from the spirit and scope of my invention. 105

What I claim as new and desire to secure by Letters Patent is:

1. In a secondary clock, a rotatable step-by-step disk having a concentric series of through holes, a spring pressed locking pin adapted to enter said holes to hold the disk against rotation, a magnetically movable member on the opposite side of the disk having a free end adapted to enter said holes and push said locking pin out to unlock the disk, and means for moving said free end of the member after the disk is unlocked to rotate said disk a definite distance. 110

2. In a secondary clock, a rotatable step-by-step disk, having a circumferential series 120 of holes, a spring pressed locking pin entering said holes from one side of the disk, a spring held longitudinally movable disk actuating member, electromagnetic means for actuating said member, a projection on 125 said member adapted to enter said holes and push said locking pin out, cam means on said member and co-operating fixed cam means for forcing the said end of said member transversely against the action of its 130

holding spring after it has unlocked the disk to rotate the disk a predetermined amount.

3. In a secondary clock, a step-by-step rotatable disk having a circumferential series of holes, a spring pressed locking pin entering said holes to lock the disk against rotation, and an electromagnetically operated armature movable back and forth relatively to said disk, a spring held disk actuating member having one end pivotally connected to said armature for movement toward and from the disk, a fixed member having a guide slot in which the free end of said disk actuating member is transversely guided, the free end of said actuating member being adapted to enter said holes in the disk to engage the locking pin and push it out, and cam means for causing a transverse movement of said free end of said actuating

member after it has advanced far enough to unlock the disk, to rotate the disk a definite amount.

4. In a secondary clock, a rotatable step-by-step disk having a concentric series of 25 holes, a dial in front of the disk, a fixed support between the disk and dial, a spring pressed locking pin mounted on said support and adapted to enter said holes to lock the disk, said dial having a slot, cam means 30 on said support for withdrawing said pin against the action of its spring, and a projection on said cam means extending through said slot in the dial for manually moving said cam into and out of active position. 35

In witness whereof, I hereunto subscribe my name this 17th day of May A. D. 1917.

ALFRED L. SOHM.
